UNITED STATES PATENT OFFICE.

EDWARD G. WATKINS, OF GARDNER, MASSACHUSETTS.

DESIGN FOR CANE FABRIC.

SPECIFICATION forming part of Design No. 26,478, dated December 29, 1896.

Application filed November 27, 1896. Serial No. 613,709. Term of patent 7 years.

To all whom it may concern:

Be it known that I, EDWARD G. WATKINS, of Gardner, in the county of Worcester and State of Massachusetts, have invented and produced a new and original Design for Cane Fabric, of which the following is a specification.

Reference is to be had to the accompanying drawing, forming a part of this specification, which shows a piece of cane fabric with my design applied.

The leading feature of my design consists of the parallel stripes or bars a a , arranged in pairs, and the intersecting stripes b , all of a contrasting color from the body of the fabric, the stripes or bars a a being depressed to show the body of the fabric in the form of marginal and central squares on each side of the stripes b , and the latter showing through the body of the fabric in the form of checks.

f represents a fabric showing my design, consisting of the relatively wide parallel stripes a a and the intersecting stripes b of a contrasting color from the body of the fabric. The stripes b show through the body of the fabric in the form of checks, while the body of the fabric shows through the stripes a , between the stripes b , as a row of checks a a .

I claim—

The design for cane fabric, as herein shown and described.

In testimony whereof I have signed my name to this specification, in the presence of two subscribing witnesses, this 18th day of November, A. D. 1896.

EDWARD G. WATKINS.
